BAGGAGE REGISTER FOR PORTERS

George F. Russell, Richmond Hill, N. Y.

Application February 24, 1941, Serial No. 380,234

2 Claims. (Cl. 235—1)

This invention has general reference to indicating and registering devices and refers more particularly to a register for indicating the number of pieces of baggage being carried by a porter and for counting the total number of pieces carried over a given period of time.

Under the present practice, porters in railway, air and bus terminals are paid by the terminal on an hourly or daily basis with each piece of baggage carried being charged for and the fees collected becoming the property of the porter's employer. Under this system, porters are usually provided with baggage checks and stubs, the checks being attached to the baggage as a receipt for the fees and the stubs being turned in by the porter together with the fees collected.

The present invention comprehends a baggage register adapted to be worn by a porter and provided with means adapted to be manually set by the porter for displaying indicia corresponding to the number of pieces of baggage being carried, together with means for counting the total number of pieces carried over a given period of time.

With the above enumerated and other objects in view, the invention is set forth in greater detail in the following specification and illustrated in the accompanying drawing in which:

Fig. 1 is a perspective view of the baggage register worn by a porter.

Fig. 2 is an enlarged front view thereof.

Fig. 3 is a vertical sectional view thereof taken approximately on the line 3—3 of Fig. 5.

Fig. 4 is a similar view with parts broken away and shown in section to disclose the underlying structure.

Fig. 5 is a vertical sectional view taken approximately on the line 5—5 of Fig. 2.

Fig. 6 is a horizontal sectional view taken approximately on the line 6—6 of Fig. 4.

Referring to the drawing by characters of reference, 10 designates generally a baggage register casing having a front wall 11, a marginal wall 12 and a rear wall 13, the latter being provided with belt loops 14 for mounting the register on the porter's belt.

The front wall 11 of the casing is provided with a window opening 15 which is preferably covered by a transparent panel 16 to exclude dust, dirt, moisture or other foreign matter from entering the window opening while affording a clear view therethrough.

The rear wall of the casing has secured thereto and protruding forwardly from the center thereof, a fixed stub shaft 17 which has mounted thereon for turning movement with reference

thereto a sleeve 18 which is provided at the forward end with a radial arm 19. Adjacent its rear end, the sleeve is formed with an annular series of outwardly projecting ratchet teeth 20 and mounted on the forward end in front of the arm 19 is a disk-like dial element 21 which is secured to the sleeve for turning movement therewith. The dial 21 is provided on its forward face with a circumferentially spaced series of indicia or numerals 22 adapted to be selectively displayed through the window opening 15 as the dial is rotated, it being understood that the indicia corresponding to the number of pieces of baggage being carried will be displayed. The dial 21 is also formed with a peripheral notch 23 between the lowest and highest number and the register is so constructed and arranged as to normally dispose the notched portion 23 of the dial in registry with the window opening in the manner and for the purpose hereafter described.

The sleeve 18 is surrounded by a coiled spring 25, one terminal 26 of which is anchored to a stop element 27 and the other terminal of which is anchored to the sleeve to exert a tension thereon so as to effect counter-clockwise turning movement of the sleeve and dial to normally engage the arm 19 with the stop element 27 thereby disposing the notched portion 23 of the dial in registry with the window opening 15 as shown in Figs. 2 and 5.

The rear wall 13 of the casing has secured on the lower portion of the forward face thereof a counter 30 of any of the standard types provided with number disks and provided with a shaft 31 having an actuator arm 32 which, when rocked in opposite directions, actuates the number disks to display the total number of actuations. The rear wall 13 also has mounted thereon and projecting forwardly therefrom, a bell or equivalent audible signal 33 and a clapper 34 carried by an arm 35 fulcrumed at 36 and tensioned by a spring 37 to engage the bell for sounding the same when the clapper is swung away from the bell and released.

In order to provide a common means for turning the dial 21, actuating the counter 30 and sounding the bell or audible signal 33, a reciprocating slide bar 40 is mounted within the casing for transverse guided sliding movement in a bearing 41 and the same is normally retracted by a spring 42 adjacent one end thereof. The opposite end 43 of the slide bar is connected with a pull stem 44 extending through the marginal wall 12 of the casing and protruding therefrom and provided with a manipulating knob 45. The slide

bar carries a pair of pivoted spring pressed dogs 46 and 47, the former of which is adapted upon each movement of the slide bar to the left to engage with one of the ratchet teeth 20 to turn the sleeve 18 and the dial 21 a predetermined distance to successively display the indicia 22 through the window opening 15. Simultaneously with each movement, the dog 47 engages the terminal 48 of the clapper arm 35 to trip the same and sound the bell or audible signal 33. The slide bar also carries an angularly disposed flange 49 having a notch 50, the opposite end edges of which notch define shoulders 51 and 52 which are disposed for movement in a path to alternately engage the actuator arm 32 of the counter 30.

In order to releasably retain the sleeve 18 and dial 21 against retrograde or counter-clockwise movement upon each actuation of the slide bar, a detent member 55 is provided which is mounted for guided sliding vertical movement in the casing in a bearing 56 secured to the rear wall 13 thereof. The detent 55 is provided with an angularly disposed terminal 57 at its upper end and a spring 58 normally urges the detent 55 into engagement with the ratchet teeth 20 of the sleeve 18. A pull stem 59 is attached to the angular terminal 57 of the detent and extends through an opening in the marginal wall 12 of the casing and is provided with a manipulating knob 60.

In use and operation, the dial 21 is normally set by the engagement of the arm 19 with the stop 27 so that the notched portion 23 registers with the window opening 15. This disposes the notch in alignment with the number disks on the counter 30 so that the total may be read. When the porter is engaged to carry one or more pieces of baggage, he is required to manipulate the slide bar 49 by pulling outwardly on the manipulating knob 45 to set the dial 21 to display through the window opening the indicia or number 22 which corresponds to the number of pieces of baggage being carried. Each outward pull on the knob 45 and pull stem 44 will turn the sleeve 18 the distance of one ratchet tooth to successively display the numbers or indicia 22 at the same time the bell or audible signal 33 will be sounded and simultaneously the shoulders 51 and 52 will successively engage with the manipulating arm 32 of the counter 30 to register thereon each manipulation of the slide bar 49 so that the total number carried during a given period of time may be estimated by readings on the counter. After each engagement, the porter resets the register by pulling outwardly on the manipulating knob 60 to retract the detent 55.

This releases the detent from engagement with the ratchet teeth 20 and permits the spring 25 to turn the sleeve 18 in a counter-clockwise direction until the arm 19 again engages the stop element 27 thus disposing the notched portion 23 again in registry with the window opening 15.

From the foregoing it is thus apparent that a baggage register has been devised by means of which the number of pieces being carried on each engagement is clearly displayed and by means of which the total pieces carried over a given period of time may be estimated by the employer.

What is claimed is:

15. In a baggage register for porters, a casing having a window, a counter within the casing having indicia bearing faces aligned with the window for display therethrough, an indicia bearing element having an opening therethrough and 20 having the indicia thereon and the said opening spaced relative to each other, said element being so mounted for movement within the casing as to selectively dispose either the indicia thereon or said opening in alignment with the window 25 so as to display the indicia on said element when said indicia is in alignment with the window and to display the indicia on the counter faces through said opening and window when the opening is disposed in alignment with the window 30 and counter, and a common manipulating means for actuating the counter and indicia bearing element in unison.
2. In a baggage register for porters, a casing 35 having indicia bearing faces aligned with the window for display therethrough, an indicia bearing element having an opening therethrough and having the indicia and said opening spaced relative to each other, said element being so mounted 40 for movement within the casing as to selectively dispose either the indicia thereon or said opening in alignment with the window so as to display the indicia on said element when said indicia is in alignment with the window and to 45 display the indicia on the counter faces through said opening and window when the opening is disposed in alignment with the window and counter, a normally retracted reciprocating bar mounted within the casing for guided sliding 50 movement and having an exposed manipulating terminal, and interengageable means on said bar and on said indicia bearing element and said counter for effecting manipulation of the counter and indicia bearing element in unison upon movement of said reciprocating bar in one direction.

GEORGE F. RUSSELL.
